UNITED STATES PATENT OFFICE.

EDWIN L. KINGSLEY, OF OLYPHANT, PENNSYLVANIA.

DESIGN FOR AN ACCOMPANIMENT-INDICATOR.

SPECIFICATION forming part of Design No. 33,419, dated October 23, 1900.

Application filed August 4, 1900. Serial No. 25,952. Term of patent 14 years.

To all whom it may concern:

Be it known that I, EDWIN L. KINGSLEY, a citizen of the United States, residing at Olyphant, in the county of Lackawanna and State of Pennsylvania, have invented and produced a new and original Design for an Accompaniment-Indicator; and I do hereby declare the following to be a full, clear, and exact description of the invention, such as will enable others skilled in the art to which it appertains to make and use the same.

In the drawings, Figure 1 is a front view of the accompaniment-indicator. Fig. 2 is a cross-section taken on the line $x-x$ in Fig. 1.

As shown in the drawings, the leading or material features of the design consist of a bar which in cross-section is shaped like an arrow-head and which has on its surface a series of parallel lines arranged horizontally in pairs, blocks arranged at intervals in the spaces between each pair of parallel lines, and

heavy-faced vertical lines leading downward from the said blocks to the base of the bar.

A is the bar, which has a longitudinal groove a' in its base and which is shaped in cross-section like an arrow-head. 25

B indicates the parallel lines arranged horizontally in pairs.

D indicates the blocks between the pairs of lines, and d indicates the heavy-faced vertical lines leading downward from the said blocks to the base of the bar. 30

What I claim is—

The design for an accompaniment-indicator, as herein shown and described. 35

In testimony whereof I affix my signature in presence of two witnesses.

EDWIN L. KINGSLEY.

Witnesses:

WM. H. HIMMELREICH,
J. H. FEELEY.
